Attorney

UNITED STATES PATENT OFFICE.

VITUS A. BOKER, OF MINNEAPOLIS, MINNESOTA.

THERMOSTAT.

Application filed April 2, 1925. Serial No. 20,242.

One object of my invention is to provide an improved form of thermostat that is particularly adapted for controlling the heating of the crucible of type setting machines 5 and the like.

Another object is to provide a thermostat wherein the short but powerful movement of an expansible body operates thru lever mechanism, the contact of the thermostat.

10 Another object is to provide an improved form of contact carrying device that will insure a wiping contact between the point and the anvil.

Another object is to provide means for 15 making a contact between the point and the anvil with a quick snap instead of a slow movement.

Another object is to provide a device of 20 the class described with improved anti-friction rollers to reduce the friction in the device and increase its sensitiveness.

With these and incidental objects in view, 25 the invention consists of certain novel features of construction and combination of parts, the essential elements of which are hereinafter described with reference to the drawing which accompanies and forms a part of the specification.

In the drawing Figure 1 is a side elevation 30 of a type setting machine crucible showing the position in which my improved thermostat would be installed. Figure 2 is an end view of my thermostat and Figure 3 is a section taken on the line 3-3 Figure 2. 35 Figure 4 is a side view of the lower portion of the thermostat. Figure 5 is a top view of a modification of my improved thermostat and Figure 6 is a front view of the same with a portion of the frame broken away.

40 The thermostat consists of a frame 1, in which is mounted the horizontally extending tube 2, carrying the element 3.

The bell crank 4 is hinged to the frame 1 at 5 and carries a set screw 6 contacting 45 with the free end 7 of the member 3, the opposite end of which is in contact with the closed end of the tube 2.

The link 8 is hinged at 9 to the bell crank 4 and at its opposite end is hinged to the lip 50 10 of the lever 11.

This lever of the general U shape, having one long end which forms the arm 11 and a short end which forms the lip 10 and is hinged at 12 to the frame 1.

55 The face 13 of the arm 11 contacts with the roller 14 carried by the arm 15 which is

hinged at one end 16 to the frame and carries at its opposite end the inner end 17 of the spiral spring 18, which in turn carries a double pointed contact 19 at its outer end 60 on the lip 20.

The clip 21 carries one end of the tension spring 22 the other end of which is secured to the arm 15, thus holding the roller 14 in contact with the face 13. 65

The adjusting screw 23 mounted on the frame contacts with the lip 20 and delays its motion in either direction until a predetermined amount of tension has been set up in the spiral spring 18 and anvil contacts 24 70 and 25 are provided for making contact with the double points 19 as the arm 15 is moved to the right or left.

Looking at Figures 2 and 3, it will be noted that the compression spring 26 interposed between the frame member 27 and one arm of the bell crank 4, maintains the set screw 6 in contact with the end 7 of the expansible element. 75

From the description and drawing, it will 80 be seen that if the tube 2 expands as it does to a greater extent than the element 3, the bell crank 4 will be moved in a counter-clockwise direction looking at Figure 3, and that the lever 11 will thereby be moved in a 85 clockwise direction causing the lip 20 to snap from the point of the screw 23 and make contact with the anvil 25. Conversely, when the pipe 2 contracts with the element 3 contracting a lesser amount, the bell crank 4 will be moved in clockwise direction and the lever 11 will thereby be moved in counter-clockwise direction and the tension spring 22 will cause the lever 15 to swing in counter-clockwise direction, thus causing 90 the lip 20 to snap past the screw 23 and contact against the anvil 24. 95

In the modification shown in Figures 5 and 6, the mechanism is the same throughout with the exception of the construction 100 of the arm 15.

In the modification the arm carries at its upper end, a semi-flexible member 18' on which is mounted the double contact 19' and the lip 20'. The insulated stud 50 is mounted on the frame and adjustably mounted therein is a carrying bracket 51 on which is adjustably mounted the clip 52. 105

The other end of this clip 52 is tensioned against the adjusting screw 53, mounted in 110 the stud 54.

Fastened to the clip 52 by means of the

screw 55, or in any other suitable manner, is a spring 56 which has an angular lip 57 formed near its opposite end, this lip projecting thru an aperture in the clip 52, so 5 the lip 20' can impinge thereagainst when the arm 15' moves in either direction.

I find that this construction gives greater sensibility of adjustment as the tension may be readily varied and also the position either 10 vertically or horizontally of the lip 57 may be readily varied.

While I have described my invention and illustrated it in one particular construction, 15 I do not wish it understood that I limit myself to this particular embodiment, as it is evident that the application of the invention may be varied within the scope of the following claims.

I claim:

- 20 1. In a thermostat, the combination with a frame, of an expansible element carried thereby, a bell crank hinged to said frame and having one end contacting with the free end of said expansible element, resilient means for maintaining contact between said 25 expansible element and said bell crank arm, a link hinged to the opposite end of said bell crank, a second lever hinged to said frame and having one end thereof hinged to the free end of said link, a contact lever arm hinged to said frame, a roller carried 30 by said contact lever arm, the free end of

said second named lever contacting with said roller and resilient means for maintaining said roller in contact with said lever 35 arm.

2. In a thermostat, a pair of contact anvils, a thermostatically controlled arm normally positioned intermediate the anvils, a double contact point carried by the arm and alternately engageable with the anvils, said contact point being flexibly carried by the arm whereby it will have a wiping contact with the anvil to which it is carried by the arm, and means engageable with the arm after one contact has been broken for delaying the contact between the point and the other of the anvils until the arm has been thermostatically actuated to a predetermined extent. 40 45 50

3. In a thermostat, a contact anvil, a movable arm, a contact point for engagement with the anvil, a flexible member carried by the arm to support the contact point, thermostatically controlled means for moving the arm toward the anvil, a stop for delaying the movement of the contact point toward the anvil until after the arm has been moved a predetermined distance toward the same, said delaying stop being adjustable whereby the moment of contact between the contact anvil and the contact point may be regulated. 55 60
